UNITED STATES PATENT OFFICE.

HERMAN H. ASHINGER, OF SOUTH BEND, INDIANA, ASSIGNOR TO GEORGE CUTTER COMPANY, OF SOUTH BEND, INDIANA, A CORPORATION OF INDIANA.

LIGHTING SOCKET AND HOLDER.

1,266,651.

Specification of Letters Patent. Patented May 21, 1918.

Application filed August 1, 1917. Serial No. 183,904.

To all whom it may concern:

Be it known that I, HERMAN H. ASHINGER, a citizen of the United States, residing at South Bend, in the county of St. Joseph and State of Indiana, have invented a certain new and useful Improvement in Lighting Sockets and Holders, of which the following is a specification.

My invention relates to lighting sockets and holders, especially those intended for industrial use in factories, warehouses and similar places. My device constitutes a combined socket and reflector holder, and the general object of the invention is to provide a device of this character which shall have practically universal application and which shall be structurally simple and easy to install and work with. It will be understood by those familiar with the art that in incandescent lighting, especially in industrial buildings, the supply conductors lead to an outlet box, and that sometimes it is desirable to locate the lamp bulb close to or substantially at the outlet box, while at other times, it is desirable to bring the bulb lower down into the room. For this purpose a down pipe or stem is usually employed, the bulb being mounted at the lower end of it. One of the specific objects of my invention is to provide a socket which lends itself with particular facility to being attached either to the outlet box itself or to the lower end of the down pipe or stem. In my present form of device the conductive shell into which the lamp base screws is housed within a block or porcelain which may be attached either to the outlet box or to a hood flange carried at the lower end of the stem, the attaching means being independent of the parts which perform any electrical function or which serve to fasten the reflector holder to the insulating block. Another object of the invention is to provide a construction in which the supply conductors lead through the body of the insulating block to the bottom thereof so that they may be connected or disconnected by simply manipulating a screw driver from underneath the block. This makes it possible to establish the electric connection after the insulating block has been mounted in place. Another object is to provide a reflector holder of special design having its own individual means of attachment to the block and having quick

acting and efficient means of attachment to 55 and detachment from the reflector holder.

I accomplish my objects by the mechanism illustrated in the accompanying drawings, in which:

Figure 1 is an axial section of the assembled device showing it fastened to the lower end of a stem and having a lamp bulb and reflector in position. The plane of section is indicated by the line 1—1 Fig. 3.

Fig. 2 is an axial section on the line 2—2, 65 Fig. 3.

Fig. 3 is a bottom plan of the parts shown in Fig. 2.

Fig. 4 is a plan section on the line 4—4, 70 Fig. 1.

Fig. 5 is a perspective of the threaded shell and the electric connections therefor.

Fig. 6 is an axial section on the line 6—6, 75 Fig. 3.

Fig. 7 is an axial section similar to Fig. 1, 75 but showing the device fastened to an outlet box instead of to the stem of the fixture.

Fig. 8 is a perspective showing the principle of operation of the shade holding ring.

Fig. 9 is a plan section on the line 9—9, 80 Fig. 7.

Fig. 10 is a perspective of the ring employed for fastening the porcelain block to the outlet box.

Similar numerals refer to similar parts 85 throughout the several views.

In the form selected to illustrate the invention, the block 1, which forms the principal element of the structure, is of porcelain or other insulating material. It is chamfered at the bottom to receive and circumferentially inclose a metallic shell 2, which is threaded to take the base 3 of the lamp 4, which is of standard pattern. The electric connections of said shell are best shown in 90 Fig. 5 where it will be seen that the shell is connected to one of the supply conductors 5 by means of a screw 6 screwing into a strap 7 electrically connected to binding post 8. The head of this binding post comes at the 95 bottom of the block and the supply conductor is led down to it through the vertical aperture 9, as best shown in Fig. 2. The other supply conductor is led in a similar way down through the aperture 10 in the block to 100 the binding post 12, which connects through the strap 13 and screw 14 to the center contact 15 of the socket. The advantage of this

construction lies in the fact that the final connections of the installation may be made at the bottom of the block after said block has been fastened in final position.

- 5 The reflector holder of my device consists of a ring 18 having inwardly projecting lugs 19 which receive screws 20 by which the holder is fastened to the block 1. The inner ends of the screws or studs 20 enter nuts 21 held in chambers 22 formed in the block, as best shown in Figs. 2 and 7. It will be noted that by this construction, the reflector holder and the block become a unitary structure held together independently of the 15 condition of the rest of the device.

The reflector holder is of special construction, having two lugs 24 extending radially inward and adapted to engage the flange 25 of the reflector 26. By preference, these 20 lugs are arranged about 120° apart, and opposite to them is a single set screw 27. This construction greatly simplifies the act of attaching or detaching the reflector, for all that is necessary in attaching it is to place 25 the flange of the reflector upon the two lugs as suggested in Fig. 8, then swing the opposite edge of the flange up to the set screw and then screw in said screw. Similarly, by backing up the screw, the reflector may be 30 removed. Not only is the manipulation simplified, but the certainty and security of action is increased because the lugs, being a permanent part of the reflector holder, are in no danger of becoming loosened or being 35 improperly positioned, as set screws are apt to be.

The block 1 and shade holder 18 and shell 2 will usually be assembled at the factory and hence constitute a unit ready for the reception of the lamp and the reflector and ready for attachment to the fixed electrical connections attached to the building. This unitary structure of the block, shell and shade holder may be attached either to the 45 hood-flange 30, shown in section in Figs. 1, 2 and 6, or to the outlet box 35, shown in Fig. 7. The hood-flange is so named on account of its shape, and screws onto the lower end of the stem 31 which leads the supply 50 conductors to the fixture. Said flange is tapped to take the upper threaded end of the screws 32, shown, for example, in Fig. 1. The heads of these screws rest in sockets 33, formed in the bottom of the block 1. If the 55 lamp is to be mounted at the ceiling instead of at the lower end of the stem 31, it will be attached directly to the outlet box 35 through the medium of the plate 36, shown in Figs. 7, 9 and 10. This plate is annular 60 and has lugs 34 into which screw the studs

or screws 32, previously mentioned. The plate has slots 37 for accommodating studs 38 which screw into the outlet box, as best shown in Fig. 7. By preference, these slots are enlarged at one end to pass the heads of 65 studs 38. This construction affords something analogous to a bayonet-joint, for, to remove the plate, it is unnecessary to actually remove the studs. All that is necessary is to loosen the studs a trifle, rotate the plate 70 a few degrees and permit it to drop free and clear of the outlet box. The supply conductors 5 are connected, as before, to the lower end of the binding posts 8 and 12. When designed to be attached directly to 75 the outlet box, the plate 36 will be permanently attached to the block 1 by means of the screws 32 and in such case the plate would become a part of the unitary structure of which the other principal parts are 80 the block, shell and the reflector holder.

It will be seen from the foregoing that the structure as a whole is greatly simplified over previous devices for the same purpose, and is simpler not only in construction, but 85 is also easier to use and to install.

Having thus described my invention, what I claim as new and desire to secure by Letters Patent, is:—

1. A lighting socket having a block of insulating material, lamp-engaging terminals housed within said block, binding posts connected to said terminals and having means at the bottom of the block for attachment to the supply conductors, said block being vertically apertured to permit the supply conductors to pass down through the block to the lower end of the binding posts, a plate fastened to the top of said block and projecting beyond the edge of the block, and means on the projecting portion of said plate for attaching the same to a supporting object. 90 95 100

2. A combined lighting socket and reflector holder consisting of a block of insulating material having terminals for the lamp housed therein, binding posts having heads at the bottom of the block, said block being vertically apertured to permit the supply conductors to pass down through to the lower end of the binding posts, a reflector-holding ring having independent fastening means for securing it to the block, and means independent of the binding posts and independent of the means which fasten the reflector-holding ring to the block, for supporting said block. 105 110 115

In witness whereof, I have hereunto subscribed my name.

HERMAN H. ASHINGER.
